By *David O. Barnell*,
Attorney.

UNITED STATES PATENT OFFICE.

THORWALD B. PETERSON, OF OMAHA, NEBRASKA, ASSIGNOR TO THORWALD MANUFACTURING COMPANY, OF OMAHA, NEBRASKA, A COPARTNERSHIP COMPOSED OF T. B. PETERSON, C. E. STIEFFLER, AND W. E. DOUGHERTY, ALL OF OMAHA, NEBRASKA.

ELECTRICAL HEATER FOR CARBUREETERS.

1,280,290.

Specification of Letters Patent.

Patented Oct. 1, 1918.

Application filed October 7, 1916. Serial No. 124,422.

To all whom it may concern:

Be it known that I, THORWALD B. PETERSON, a citizen of the United States, and a resident of Omaha, in the county of Douglas and State of Nebraska, have invented certain new and useful Improvements in Electrical Heaters for Carbureters, of which the following is a specification.

My invention relates to carbureters such as are used in connection with internal combustion engines for forming an explosive charge by vaporization of volatile fuel-oils such as gasoline. It is the object of my invention to provide electrical heating means, readily attachable to the bowl or float-chamber of an ordinary carbureter, and adapted to quickly heat to boiling temperature the oil contained in said chamber, thereby facilitating the starting of the engine in cold weather, or facilitating the vaporization of heavier fuel-oils at any time. Further objects of my invention are to provide a simple and inexpensive device of this kind, having a heating coil immersed in the fuel-oil, and having special means for causing a rapid circulation of the oil around and past the heating coil.

In the accompanying drawings Figure 1 is a vertical sectional view of a portion of a carbureter provided with an electrical heating device embodying my invention, the device being shown on an enlarged scale, and the electrical heating-circuit being represented diagrammatically, and Fig. 2 is a detail horizontal section on the plane of the line 2-2 of Fig. 1.

In most of the carbureters now in common use in motor-vehicles and the like, the bowl or float-chamber of the carbureter is provided at the lowest part thereof with a threaded opening for receiving a drain-cock, and with such carbureters I prefer to attach my heating device by removing the drain-cock and screwing the casing of the heating device into the threaded opening from which the cock is removed. Where such an opening is not provided in the bowl of the carbureter, it is a simple matter to drill and tap a suitable hole in the lowermost portion of the bowl, to receive the threaded neck of the heater-casing.

In the drawing there is represented the lower portion 3 of the bowl or float chamber

of a carbureter, having such a threaded opening as above mentioned. The heater has a bottle-shaped casing 4 with a threaded neck-portion 5 which is screwed into the threaded opening of the carbureter-bowl 3. Within said casing 4 there is a thimble-shaped shell or hood 6 disposed in spaced relation to the walls of the casing, and having at its lower end an annular flange 7 which fits within the lower end of the casing and is permanently affixed thereto by sweating or welding so as to be substantially integral therewith. The casing preferably has at its lower end a hexagonal portion 8 so as to be conveniently engaged by a wrench when screwing the same into the bowl 3. In the upper end of the hood 6 there is an opening into which is fitted the lower end of a tube 9, the latter being secured in the opening by swaging or expanding the material thereof against the sides of the opening. The tube 9 extends from the top of the hood up through the neck 5 of the casing, in spaced relation to the sides of said neck, and terminates in the bowl considerably above the bottom thereof, as shown. In the sides of the hood near the flange 7 there are a plurality of radial openings 10 which afford communication between the space within the hood and that surrounding the same between the body thereof and the walls of the casing. The lower end portion of the hood is threaded internally to receive a threaded plug 11 having a flange-portion 12 extending beneath the flange 7 of the hood, and preferably a washer or gasket 13 of suitable material is disposed between said flanges to insure the prevention of leakage past the threads of the plug. The plug 11 has a central threaded opening in which is screwed the lower end of an externally-threaded perforate core 14 of insulating material, the body of which extends up within the hood, as shown. Within the helical groove formed by the threading of the body of the core above the plug 11, there is wound a coil of wire 15 of which the lower terminal is inserted and secured in a hole 16 in the plug 11, while the upper terminal is held at the upper end of the core beneath the head of a screw 16. Said screw extends down through the central opening or perforation of the core 14 and the lower part thereof has a nut 17 which is screwed firmly

against the end of the core. The lower end of the screw is extended beyond the nut 17 to form a binding-post on which is screwed a knurled binding-nut 18 adapted to hold 5 the end of a wire between the same and the nut 17.

The heating-coil formed by the wire 15 is supplied with electrical energy from a storage battery 19, or other suitable means, one 10 terminal thereof being connected by a wire 20 with the screw 16, and the other terminal of the battery or generator being suitably connected by a wire 21 with the plug 11 or any part of the casing, carbureter or engine 15 which is in electrical connection with said plug. Any suitable switch 22 is provided for controlling the heating circuit.

The operation of the device will be readily understood. The wire 15 is so proportioned 20 that when the circuit through the same is closed by operation of the switch 22, the coil will be almost instantly heated by the electric current flowing therein, and the heat of the coil will be communicated to the oil surrounding the coil within the hood 6. The heated oil, being lighter than an equal volume thereof at lower temperature, will rise up through the hood and the extension-tube 9, thus passing into the upper part of the bowl 3, while the cooler oil from the lower part 30 of the bowl will flow downwardly through the neck 5 of the casing, around the outside of the hood 6, and, passing through the openings 10 at the lower end of the hood, will 35 come into contact with the heated coil. Thus there will be caused a constant and rapid circulation of the oil through the heating device, so that in a very short time the entire body of oil from the bowl 3 will be heated 40 to the desired temperature at which vaporization thereof will readily occur when it is drawn from the bowl or float-chamber to the charge-forming devices. It should be noted that, owing to the arrangement of the wire 45 15 in the thread-grooves of the insulating core, loosening of the wire due to the expansion thereof when heated cannot result in disarrangement of the coil and short-circuiting of parts thereof by two or more of 50 the turns coming into contact with each other.

Now, having described my invention, what I claim and desire to secure by Letters Patent is:

55 1. The combination with the oil-receptacle of a carbureter, of a casing having a tubular neck-portion connected with the lower part,

of said receptacle, a hood disposed in said casing in spaced relation to the walls thereof and having an extension-tube passing up 60 through the neck-portion of the casing in spaced relation thereto and terminating within the receptacle, and an electrical heating element disposed in said hood so as to be in contact with a current of oil flowing from 65 the receptacle downwardly around the hood and extension-tube and upwardly through the same.

2. In a device of the class described, the combination with a carbureter, of a casing 70 secured to the lower end thereof and communicating therewith, a heating element within the casing, a hood encircling the heating element and provided with a circulating pipe extending into the carbureter, said hood having circulating openings therethrough adjacent its lower end whereby the gasoline which is heated by the heating element will rise through the circulating pipe and into the carbureter and cold gasoline will descend into said casing around the pipe and hood.

3. An oil-heating device for carbureters, comprising a casing having a tubular upper portion adapted for connection with the lower part of the oil-receptacle of a carbureter so that oil from the receptacle may flow down through said tubular portion to fill the casing, an electrical heating element disposed in the lower part of the casing, means 85 for connecting said heating element with a source of electrical energy, and a hood arranged around the heating element and extending therefrom through the tubular upper portion of the casing in spaced relation thereto, said hood adapted to direct heated oil up through said portion of the casing and prevent said heated oil from mingling with the oil descending from the receptacle into the casing.

4. In a heater for carbureters, the combination with a carbureter having a gasoline-containing chamber, of a casing secured thereto and communicating therewith, a heating element within the casing, and means within the casing forming a plurality of circulating passages communicating with the gasoline-containing chamber whereby the heating of the gasoline will cause it to circulate from the casing to the chamber through one passage and from the chamber back to the casing again through another passage.

T. B. PETERSON.
